POWER-OPERATED CARRIAGE RETURN
MECHANISM FOR TYPEWRITING AND
LIKE MACHINESHenry J. Hart, West Hartford, Conn., assignor to
Royal Typewriter Company, Inc., New York,
N. Y., a corporation of New York

Application April 16, 1948, Serial No. 21,476

23 Claims. (Cl. 197—66)

1

This invention relates to power operated carriage return mechanism for typewriting and like machines, and more particularly to improved means for controlling or conditioning such mechanism for operation.

In a preferred embodiment of the invention, a winding drum is arranged for reeling or winding a carriage return draw band connected to the carriage, preferably through the intermediary of a line spacing mechanism. A normally disengaged clutch is interposed between the winding drum and a continuously rotating, power driven member. Key controlled mechanism is provided for effecting engagement of the clutch so as to drive the drum, and cause a line spacing and a carriage returning movement to be performed.

An object of the invention is to provide improved means for applying clutch engaging force or effort through the medium of a resilient or yieldable force transmitting member, so as to eliminate shocks which otherwise could be caused by abrupt or positive engagement of the clutch.

Another object of the invention is to provide improved means for initiating carriage returning drive in response to depression of a key, without permitting repeated starting and stopping of the carriage returning mechanism when the key is held depressed.

Another object of the invention is to provide improved mechanism of the kind referred to which cannot be conditioned for operation if the controlling key is depressed and then released when the driving means is not in operation, thereby eliminating the possibility of a quick and unexpected return movement of the carriage taking place immediately upon connection of the driving mechanism to a source of power.

A further object of the invention is to provide mechanism of the class referred to which may readily be used in typewriters not substantially larger than present standard office typewriters.

Other objects of the invention will become apparent from a reading of the following description of a representative embodiment of the invention, the appended claims, and the accompanying drawings.

In the drawings:

Figure 1 is a view, partly in elevation and partly in vertical section, fore and aft of a typewriter embodying the invention, showing only some of the conventional or standard typewriter parts in order to illustrate the application of mechanism embodying the invention to a typewriter construction;

Figure 2 is a fragmentary view, partly in ver-

2

tical section and partly in elevation, showing a key and associated parts for controlling the operation of carriage return mechanism;

Figure 3 is a fragmentary top plan view with some parts shown in section, parts of the mechanism for controlling a carriage return clutch being shown in their inactive or normal positions;

Figure 4 is a fragmentary top plan view showing a frame part in section, and showing a carriage return clutch and associated control mechanism with the parts in their actuated or clutch engaging positions;

Figure 5 is a fragmentary detail view in elevation showing, on an enlarged scale, parts of the clutch controlling mechanism as viewed when looking in the direction of the arrow 5 in Figure 3;

Figure 6 is a section on the line 6—6 of Figure 4, showing a latch member or pawl in elevation;

Figure 7 is a fragmentary sectional view, end-to-end of the machine, on the line 7—7 of Figure 3, and showing mechanism for terminating the carriage returning drive;

Figure 8 is a transverse vertical sectional view of the clutch and associated mechanism, the section being taken on the irregular line 8—8 of Figure 1; and

Figure 9 is a vertical section on the line 9—9 of Figure 8.

The invention may be embodied in typewriters or like machines of various kinds. For the purposes of illustration, the invention is shown as being embodied in an office type typewriter having, except for the power mechanism to be described, many features in common with the well known Royal Standard typewriter. The drawings show only enough of the standard or known typewriter construction to assist in illustrating the manner in which mechanism embodying the invention may be coordinated with a typewriter construction.

The known construction illustrated includes a main frame A on which a carriage B is mounted for letter spacing and return movements by means of a top rail 1 secured to the carriage, and rolling upon balls 2, which in turn are adapted to roll on a frame-mounted bottom rail or track 3. The carriage includes the usual end plates 4 and 5 on which a platen or cylinder 6 is journaled so that it can be rotated for line spacing.

As is customary, the platen is equipped with a ratchet wheel 7 adapted to be rotated incrementally by oscillation of a pawl 8, pivoted as at 9 on a lever 10 which is mounted to rock about the axis of the platen. Normally the pawl 8

is held up and out of engagement with the ratchet wheel 7 by a shield 11 equipped with a handle 12. When the lever 10 is rocked rearwardly, the nose of the pawl 8 moves off the shield 11 to engage a tooth on the ratchet wheel 7, after which continued rocking of the lever 10 causes the pawl to rotate the ratchet wheel and the platen 6 for line spacing the work sheet. By rocking the handle 12, the shield 11 can be so positioned as to vary the point of let-off of the pawl 8, so as to adjust the line spacing mechanism for single, double, or triple line spacing in the usual manner.

The mechanism for rocking the lever 10 and line spacing pawl 8 includes a link 14 pivoted as at 15 to the lever 10, and pivoted as at 16 to a line spacing lever 17 which is mounted to rock in a horizontal plane on a shelf 18 formed on the carriage end plate 5. The lever 17 normally is held in retracted position against a stop 19 by a spring 20 interposed between a fixed hook 21 and a hook 21^a which is secured to the lever 17. Rocking of the lever 17 counterclockwise for effecting line spacing is limited by an adjustable eccentric stop 19^a.

As so far described, the line spacing mechanism is similar to that used in Royal Standard typewriters. In the standard typewriter, however, the lever corresponding to the lever 17 is formed with a forwardly projecting handle which is used by the operator for rocking the lever to effect line spacing until the lever engages the adjustable stop 19^a, after which the handle is used for returning the carriage to its line starting position. In the mechanism shown in the drawings, the lever 17 does not include such a handle, but instead is formed or equipped with an arm 22 which is positioned below the shelf 18 and is rockable in unison with and as part of the lever 17. The rear end of the lever arm 22 is equipped with an antifriction roller 23 which is disposed in a slot 24 in the bifurcated end of an operating lever 25, pivoted as at 26. Clockwise rocking of the lever 25 effects counterclockwise rocking of the lever 17 and line spacing movement of the platen 6. The usual finger knobs, one of which is shown at 27, are provided for rotating the platen manually.

Other known parts illustrated include a toothed margin stop bar 28 extending between and mounted on the carriage end plates 4 and 5, and right and left margin stop assemblies 29 and 30 respectively, mounted for adjustment along the bar 28. The left margin stop includes a latch 31 which is urged by a spring 32 so as normally to cooperate with teeth on the bar 28 for holding the margin stop in adjusted position. The latch 31 is equipped with a roller 33 adapted to be engaged by a pivoted bail 34 for releasing the latch against the urge of the spring 32, and thus enabling the stop 30 to be adjusted on the bar 28. An adjustable abutment screw 35 on the stop 30 is engageable with a cushion lever 36 pivoted as at 37 on the usual center stop 38. A spring 39 normally maintains the lever 36 in the position shown in Figure 7. The center stop 38 is pivoted as at 40 on a bracket 41 secured to the frame A.

The right margin stop 29 is similar to the left margin stop 30 and includes a latch and roller (not shown) engageable by a pivoted bail 42. An abutment screw 43 on the stop 29 is adapted to engage a line lock lever 44, which is pivoted as at 37 on the center stop 38. The margin stop setting or regulating mechanism is described in

more detail in the patent to Henry J. Hart No. 2,208,367, granted July 16, 1940.

The carriage may be driven toward the left, that is in the letter spacing direction, by any suitable mechanism, for example by a spring barrel and draw band of known or suitable construction.

In general the parts described so far do not, in themselves, constitute the present invention. The invention resides in other parts to be described, and combinations of such other parts with each other and with parts already described.

Power for returning the carriage to its line starting position at the operator's right may be derived from any suitable source, for example and preferably, an electric motor (not shown) arranged to drive a shaft 45. The shaft 45 is adapted to transmit drive through helical gears 46 and 47, housed in a casing 48 mounted on the frame A. A short shaft 49 carrying the driven gear 47 is equipped at one end with a flexible coupling generally designated 50. The coupling includes a sleeve 51 connected at its inner end to the shaft 49 by a pin 52. The outer end of the sleeve 51 is formed with opposed slots 53 which receive the end portions of a pin 54 protruding from a shaft 55 through which the pin 54 extends transversely. The shaft 55 is part of a clutch and draw band reeling mechanism generally designated 56, which is mounted on a bracket 57 secured to the frame A by screws 58. The mechanism 56 further includes a flanged drum 59 to which the end of a draw band 60 is secured. The draw band extends from the drum 59 around a grooved pulley 61 journaled on a bracket 62 supported on the frame A, and is connected by a fitting 63 to the lever 25 previously referred to.

In operation, the clutch forming part of the mechanism 56 normally is disengaged so that the draw band 60 is not wound up on the drum 59 to transmit returning drive to the carriage B. In order to return the carriage, mechanism to be described is operated for engaging the clutch, whereupon the drum 59 is rotated to wind up the band 60 and drive the carriage to the operator's right. Other mechanism is provided for automatically disengaging the clutch when the carriage reaches a predetermined point in its return travel.

In the illustrated preferred embodiment of the clutch and reeling mechanism, the shaft 55 is journaled in bearings 64-64' secured to the bracket 57. A leaf spring 66^a pressing against the left end of the shaft 55, and a thrust collar 64^b on the shaft hold the latter against longitudinal movement. The flanged drum 59 has a hub 65 which is journaled on a bearing sleeve 66 surrounding the shaft 55. The drum 59 normally is urged resiliently to rotate in a direction to reel in and thus take up slack in the draw band 60. For this purpose a spring 67 is anchored at its outer end to an annular member 68 secured to the bracket 57, and is anchored at its inner end to the hub 65.

The right hand face of the drum 59, as viewed in Figure 8, constitutes a clutch face which is disposed adjacent to, but normally is operatively disengaged from a clutch element 69 formed of suitable wear-resistant friction material. The clutch element 69 has a central opening which receives the shaft 55 freely, and is formed with opposed slots 70 into which extend the respective ends of a pin 71, projecting transversely through and secured to the shaft 55. To the right of the clutch

element 69 is a pressure plate clutch element 72 mounted to slide or shift longitudinally on and to rotate about the bearing 64'. A plurality of circumferentially spaced pins 73 are secured to the shiftable clutch element 72 and extend respectively into openings 74 in the drum 59 so as to couple the drum and the pressure plate to rotate in unison. A plurality of springs 75 are deployed circumferentially between the drum 59 and pressure plate 72 for yieldably urging the latter away from the clutch element 69.

In accordance with one feature of the invention, mechanism is provided for applying clutch engaging force to the pressure plate 72 through the medium of a resilient force transmitting connection so as to produce cushioned but nevertheless dependable and firm engagement of the clutch. In the form shown, a clutch engaging lever 77 is provided with ears 78 which are pivoted as at 79 on ears 80 formed on the bracket 57. The lever 77 has upper and lower arms equipped with rollers 81 adapted to bear against the pressure plate 72 for urging the latter against the friction element 69. The forward part 82 of the lever 77 is engaged by a roller 83 journaled on an arm 84, which is fast on a shaft 85, pivoted on ears 86 formed on a bracket 87 secured to the bracket 57. When the arm 84 is rocked counterclockwise, as viewed in Figures 3 and 4, the roller 83 presses against the end 82 of the lever 77 so as to rock the latter counterclockwise and cause the rollers 81 to press against the pressure plate 72. In this way the pressure plate is moved against the urge of the springs 75 into engagement with the friction element 69, thus squeezing the latter between the pressure plate 72 and the clutch face of the drum 59, so as to cause the drum to be driven from the shaft 55.

Force for rocking the shaft 85 for the purpose set forth above is transmitted by a clutch engaging device including a resilient or yielding connection. In the form shown, a latch lever arm or part 88 is pivoted loosely on the shaft 85 and is formed with an ear 89 providing an anchorage for one end of a spring 90, the other end of which is secured to an ear 91 on a latch follower lever 92 secured to the shaft 85. The spring 90 is loaded under tension, and tends to rock the part 88 and latch follower part 92 in opposite directions, so as normally to hold the parts 88 and 92 in the positions shown in Figure 3 with a stop ear 93 on the lever 92 engaging a stop ear 94 on the arm 88. When the latch lever arm 88 is rocked counterclockwise from the position shown in Figure 3 to the position shown in Figure 4, the ear 89 pulls on and additionally loads the spring 90 so as to urge the follower lever 92 resiliently to rock counterclockwise. This tends also to rock the shaft 85 and with it the roller arm 84, which in turn tends to rock the lever 77 to effect engagement of the clutch. Inasmuch as the effort for engaging the clutch has to be transmitted through the spring 90, the application of clutch engaging force is cushioned, and smooth operation is assured.

Force for rocking the lever 88 is provided by power actuated means generally designated C. The mechanism C includes a lever 95 which is pivoted as at 96 on a part of the frame A. A spring 97 interposed between the bracket 57 and the lever 95 normally maintains the latter against the adjustable stop plate 98 in the position shown in Figure 1. The lever 95 is actuatable in a manner to be described to be rocked counterclockwise, as viewed in Figure 1, to pull forwardly on a link

98 pivoted as at 99 to the lever 95 and as at 100 to a latch actuator 101 which is mounted to rock loosely on the shaft 85. The actuator 101 has one-way motion transmitting connection with the latch arm 88. To this end, the part 101 is formed with a downwardly extending projection 101a disposed behind the latch arm 88 so that, when the actuator 101 is rocked counterclockwise by forward motion of the link 98, the projection 101a presses against the latch arm 88 so as to rock the latter counterclockwise and transmit clutch engaging effort through the spring 90 in the manner previously described.

Collars 85a on the shaft 85 position the latter with respect to the bracket ears 86, and serve as spacers for locating the actuator 101, the latch lever 88, and the latch follower lever 92.

The lever 95 is rocked only momentarily for pulling the link 98 forwardly, and does not hold the link in its actuated position. In order that the clutch may be maintained engaged until the carriage has reached the end of its return movement, means is provided for holding or latching the arm 88 in the actuated position shown in Figure 4. For this purpose, a latch or pawl 102 is pivoted as at 103 on the bracket 57, and is formed with a slot 104 in which the arm 88 is movable. The latch 102 is provided with a shoulder 105 adapted to engage an edge of the arm 88 for holding the latter in its actuated position as shown in full lines in Figure 6. A spring 106, connected between the bracket 57 and the rear end of the latch 102, urges the latch to rock clockwise as viewed in Figure 6, so as to move the shoulder 105 into position for engagement with the arm 88 when the latter has been moved toward the open end of the slot 104 and beyond the shoulder 105. A stop 107 on the bracket 57 is engageable by the latch 102 for limiting its rocking under the urge of the spring 106.

In order to cause the latch 102 to release the latch lever or arm 88 when the carriage reaches the end of its return travel, a knock-off lever 108 is pivoted on the frame A as at 109, and is formed with a heel 110 which is disposed under an ear 111 on the latch 102. A link 112 is pivoted as at 113 to the knock-off lever 108, and as at 114 to a depending arm 115 on the cushion lever 36. In operation, when the carriage is being returned, the latch arm 88 and associated parts will be in the actuated positions shown in Figure 4, with the arm 88 being held in actuated position by the latch 102. Just before the carriage reaches the end of its return movement, determined by the setting of the margin stop 30, the abutment screw 35 on the stop will engage the upper end of the cushion lever 36 so as to rock the latter against the urge of the cushioning spring 39. The spring 39 serves not only to maintain the lever 36 and its associated parts in normal positions, but also to snub or bring the carriage to rest without harmful shock. Rocking of the lever 36 moves its depending portion 115 clockwise as viewed in Figure 7 to pull the link 112 and rock the knock-off lever 108, thus depressing the slotted end of the latch 102, and releasing the latch lever 88. At this time the lever 95, link 98 and latch actuator 101 will be in their normal or inactive positions as shown in Figures 1 and 3, so that releasing of the latch member 88 will permit the clutch springs 75 to move the pressure plate 72 out of engagement with the friction element 69, thereby terminating the carriage return drive.

The power driven mechanism C is generally similar to mechanism disclosed in the copending

application of William H. Kupper, Serial No. 6,066, filed February 3, 1948. It includes a driving element, which operates continuously, and controllable driving connections, which normally are inoperative or ineffective, but which may be conditioned by the operator to effect operative driving connection between the continuously moving driving member and the latch actuator link 98. The driver is constituted by a continuously rotating element, more particularly a toothed snatch roll or bar 116, which may be of known form, and which is adapted to be driven in the direction of the arrow *a* in Figure 1 by any suitable means, but preferably by the same source of power as that which drives the shaft 45.

The connections for transmitting drive from the driver 116 to the link 98 include an actuator 117 which extends fore-and-aft of the typewriter and above the member 116. The actuator is pivoted as at 118 to the lever 95 at a point offset relatively to the pivot 96. The actuator has a forwardly extending part 119 projecting under an abutment or guide plate 120 mounted by screws 121 on the frame A, to extend parallel to the snatch roll 116. A spring 122, interposed between the front end of the actuator 117 and an anchor plate 123, yieldably urges the actuator to rock clockwise, and thus normally maintains the actuator in the position shown in Figure 1 with its front end part 119 bearing against the abutment of guide plate 120. Another abutment 124 is disposed below the abutment 120 so as to underlie the actuator front end part 119.

In order to drive the link 98 to clutch-engaging position, the actuator 117 is operatively but indirectly connected to the driving member 116, the actuator itself never engaging the driving member. Mechanism for bringing about the operative connection of the actuator 117 to the member 116 includes an interponent pawl 125, which is pivoted as at 126 on the actuator. A spring 127, anchored to the actuator 117 and connected to the pawl 125, biases the latter to rock clockwise so as to move its nose into engagement with the snatch roll 116. Normally, the pawl is maintained out of engagement with the snatch roll by the restraining action of a control element or trigger 128 which is pivoted as at 129 on the actuator 117. In the normal position of the trigger, its rear end 130 engages a holding surface 131 on the pawl so as to prevent the spring 127 from rocking the pawl into drive-transmitting engagement with the driving member 116. The pawl 125 is formed with an inclined cam face 132 which is located just below the holding surface 131, and which is acted upon by the trigger for rocking the pawl counterclockwise, and thus resetting it in normal, inoperative position.

Key controlled means is provided for bringing about operative driving connection between the driver 116 and the actuator 117. This means includes a key 133 pivoted as at 134 on a rod carried by the frame A. The key 133 has an upward projection 135 disposed behind an arm 136 of an operating lever 137, pivoted as at 138 on a frame-mounted cross bar 139. The lever 137 has another arm 140 on which a limber dog or flipper 141 is pivoted at 142. A spring 143 urges the limber dog 141 to rock clockwise to yieldably retain it in its normal position of rest against a limit stop 144. The dog 141 can swing counterclockwise from the position shown in Figure 1, but cannot move clockwise from this position. A returning spring 145, interposed between the key 133 and a short arm 146 on the lever 137, yieldably holds the lever 137 in its normal position with a fourth arm 147 of the lever 137 engaging the cross bar 139. In the normal position of the parts, the lower end of the limber dog 141 overlies a contact surface 148 on the actuator 117.

lever 133 and a short arm 146 on the lever 137, yieldably holds the lever 137 in its normal position with a fourth arm 147 of the lever 137 engaging the cross bar 139. In the normal position of the parts, the lower end of the limber dog 141 overlies a contact surface 148 on the actuator 117.

In operation, when the key 133 is depressed, the lever 137 is rocked clockwise to cause the flipper 141 to push the actuator 117 downwardly to an extent sufficiently to bring the trigger 128 into engagement with the abutment 124. This causes the trigger to be rocked clockwise, so as to release the pawl 125, which is then moved by the spring 127 into engagement with the snatch roll 116. The snatch roll then drives the pawl 125 and actuator 117 as a unit so as to rock the lever 95 and pull the link 98 forwardly to effect engagement of the clutch, as previously described. When the pawl 125 is cast off from engagement with the snatch roll 116, the spring 122 lifts the actuator 117 to bring the trigger 128 into engagement with the upper, trigger-resetting abutment 120. This causes the trigger 128 to be rocked counterclockwise, so as to move its end 130 against the resetting cam face 132 of the pawl 125, thereby restoring the latter to its inactive position. The parts of the mechanism C will then be returned to their normal positions by the spring 97.

The mechanism for engaging the clutch is conjointly responsive to and dependent upon concurrent operation of the power drive mechanism and depression of the key 133. Thus, if the key 133 should be depressed, and then released when the snatch roll 116 is not operating, the pawl 125 will not be allowed to remain in engagement with the snatch roll, but will be returned to its normal position upon releasing of the key 133. Consequently, there is no danger that the carriage returning mechanism can be conditioned for operation in such a way that connecting the drive motor to a source of power will result immediately in unexpected operation of the carriage returning mechanism. This advantage is obtained even though the power mechanism C is of the kind including a spring urged pawl carried by the actuator, which has the additional advantage of assuring complete and proper engagement of the pawl with the snatch roll without danger of rasping of the parts in the event the key 133 should be depressed only partially.

It will be observed also that, if the key 133 is depressed and held down, only one operation of the lever 95 will take place. This is because when the actuator 117 is moved forwardly and returned while the key is held down, the return of the actuator will cause the flipper 141 to be rocked idly toward the rear without being returned to cooperative relation with the contact surface 149.

Operation

Although the operation of the several groups or assemblies of parts embodied in the mechanism has been described, a recapitulation of the operation of the entire mechanism may be of further aid in understanding the entire invention. When the typewriter is conditioned for operation, the parts will be in the positions shown in Figures 1, 2, 3, 5, 7, and 8, and the driver 116 and shaft 45 will be rotating concurrently. Typing will be performed in the usual manner, and the carriage will be moved in the letter spacing direction without being restrained by the carriage returning mechanism, except for the minor inci-

dental restraint due to tensioning of the draw band 60 by the slack take-up spring 61. When the carriage reaches the end of its letter spacing travel, the abutment screw 43 will engage the line lock lever 44 which will move against the center stop 38 to operate the line lock mechanism (not shown) and bring the carriage to rest.

In order to rotate the platen 6 for line spacing, and then return the carriage to its line starting position, the key 133 is depressed. This will rock the lever 137 to cause the flipper 141 to push the actuator 117 downwardly, and cause the trigger 128 to release the pawl 125, permitting it to move into drive transmitting engagement with the snatch roll 116. The pawl 125 and actuator 117 are thereby driven forwardly to pull the link 98, and rock the latch actuator 101 and latch arm 88 until the latter is latched by the latch shoulder 105. Rocking of the latch or arm 88 additionally tensions the spring 99 so as to rock the latch follower lever 92 and the clutch applying lever 77. The rollers 81 on the lever 77 thereupon push against the pressure plate 72, and move the latter against the friction element 69 to engage the clutch and rotate the drum 59, thereby winding the draw band 60 and rocking the operating lever 25 and the line spacing lever 17 to rotate the platen and line space the work sheet. When the line space lever 17 has been moved against the stop 19^a, the levers 17 and 25 can rock no further, so that continued reeling of the draw band 60 pulls the carriage toward the right, that is in the return direction. As the carriage approaches the limit of its return movement, the abutment screw 35 engages and operates the cushioning lever or snubber 36, which, through the link 112 and knock-off lever 108, rocks the latch 102 to release the latch arm 88, thereby disengaging the clutch and terminating the carriage return drive. Movement of the lever 36 against the limiting stop 38 finally will bring the carriage to rest in its line starting position.

Should it be desired to rotate the platen 6 and line space the work sheet further when the carriage is in its line-starting position, and before beginning to type a new line, it is necessary merely to depress the key 133. This will cause the mechanism C and associated parts to effect engagement of the clutch parts 72—69—59, thereby reeling the draw band 60 to actuate the operating lever 25 and the line spacing lever 17. At this time, the latch 102 will be held in its released position, shown in dotted lines in Figure 6 so that the arm 88 will not be latched in clutch-engaging position. However, the relatively brief engagement of the clutch when the arm 88 is moved forwardly will effect enough reeling of the draw band 60 to cause a line spacing operation.

The mechanism disclosed herein embodies the invention in the form which is now preferred, but it will be apparent that some changes may be made in the construction and relative arrangement of the parts within the scope of the invention as defined in the appended claims.

I claim:

1. In a power operated typewriting or like machine, a frame; a carriage mounted for letter spacing and return travel on said frame; power driven mechanism including a member which rotates continuously when the machine is in operation; normally disabled driving connections interposed between said member and said carriage and being adapted to be enabled for trans-

mitting returning drive from said member to said carriage; and manually controlled mechanism for enabling said driving connections including a power driven driver rotatable jointly with said member, an interponent biased to move into engagement with said driver, a control element normally maintaining said interponent out of engagement with said driver, a key, means responsive to depression of said key for moving said control element to release said interponent and enable it to be moved by its bias into engagement with said driver, and means responsive to return movement of said key when said driver is not rotating for returning said interponent to its normal position, whereby if said key is depressed and then returned while said driver is not rotating said interponent will not be permitted to remain engaged with said driver.

2. In a power operated typewriting or like machine, a frame; a carriage mounted for letter spacing and return travel on said frame; power driven mechanism including a member which rotates continuously when the machine is in operation; normally disabled driving connections interposed between said member and said carriage and being adapted to be enabled for transmitting returning drive from said member to said carriage; an actuator for enabling said driving connections; a driver operable concurrently with said rotatable member; an interponent connected to said actuator; means biasing said interponent to move into operative engagement with said driver; a control element normally maintaining said interponent out of engagement with said driver; a key; means responsive to depression of said key for moving said control element to release said interponent and to thereby effect operative connection of said interponent to said driver; and means responsive to return movement of said key when said driver is at rest for disconnecting said interponent from said driver.

3. In a power operated typewriting or like machine, a frame; a carriage mounted for letter spacing and return travel on said frame; power driven mechanism including a member which rotates continuously when the machine is in operation; normally disabled driving connections interposed between said member and said carriage and being adapted to be enabled for transmitting returning drive from said member to said carriage; a driver operable concurrently with said rotatable member; an actuator for enabling said driving connections; an interponent mounted on said actuator for movements into and out of operative engagement with said driver and being biased to move into engagement therewith; a trigger normally maintaining said interponent disengaged from said driver; a key; means responsive to depression of said key for actuating said trigger to release said interponent and enable it to move into engagement with said driver; and trigger re-setting means effective upon return movement of said key when said driver is at rest for moving said trigger reversely to its releasing movement and thereby disengaging said interponent from said driver.

4. In a power operated typewriting or like machine, a frame; a carriage mounted for letter spacing and return travel on said frame; power driven mechanism including a member which rotates continuously when the machine is in operation; normally disabled driving connections interposed between said member and said carriage and being adapted to be enabled for trans-

mitting returning drive from said member to said carriage; a driver operable concurrently with said rotatable member; an actuator for enabling said driving connections and being normally disconnected from said driver; a key, separate from and movable relatively to said actuator and being operative when depressed for effecting connection of said actuator to said driver; and a re-setter cam device responsive to return movement of said key when said driver is not operating for disconnecting said actuator from said driver.

5. In a power operated typewriting or like machine, a frame; a carriage mounted for letter spacing and return travel on said frame; power driven mechanism including a member which rotates continuously when the machine is in operation; normally disabled driving connections interposed between said member and said carriage and being adapted to be enabled for transmitting returning drive from said member to said carriage; a driver operable concurrently with said rotatable driving member; an actuator for enabling said driving connections; an interponent mounted on said actuator for movement into and out of engagement with said driver and being biased toward operative engagement position therewith; a re-setting cam face on said interponent; a trigger normally holding said interponent disengaged from said driver; a key; and means responsive to depression of said key for actuating said trigger to release said interponent and enable it to move into engagement with said driver, and responsive to return movement of said key when said driver is at rest for moving said trigger reversely to move a part of said trigger against said re-setting cam face and thus move said interponent from engagement with said driver.

6. In a power operated typewriting or like machine, a frame, a carriage mounted for letter spacing and return travel on said frame; power driven mechanism including a member which rotates continuously when the machine is in operation; means including a normally disengaged clutch for transmitting returning drive from said member to said carriage; and manually controlled mechanism for effecting engagement of said clutch including a power driven driver rotatable conjointly with said member, an interponent biased to move into engagement with said driver, a control element normally maintaining said interponent out of engagement with said driver, a key, means responsive to depression of said key for moving said control element to release said interponent and enable it to be moved by its bias into engagement with said driver, and means responsive to return movement of said key when said driver is not rotating for returning said interponent to its normal position, whereby if said key is depressed and then returned while said driver is not rotating said interponent will not be permitted to remain engaged with said driver.

7. In a power operated typewriting or like machine, a frame, a carriage mounted for letter spacing and return travel on said frame; power driven mechanism including a member which rotates continuously when the machine is in operation; means including a normally disengaged clutch for transmitting returning drive from said member to said carriage; an actuator for engaging said clutch; a driver operable concurrently with said rotatable member; an interponent connected to said actuator; means

biasing said interponent to move into operative engagement with said driver; a control element normally maintaining said interponent out of engagement with said driver; a key; means responsive to depression of said key for moving said control element to release said interponent and to thereby effect operative connection of said interponent to said driver; and means responsive to return movement of said key when said driver is at rest for disconnecting said interponent from said driver.

8. In a power operated typewriting or like machine, a frame, a carriage mounted for letter spacing and return travel on said frame; power driven mechanism including a member which rotates continuously when the machine is in operation; means including a normally disengaged clutch for transmitting returning drive from said member to said carriage; a driver operable concurrently with said rotatable driving member; an actuator for engaging said clutch; an interponent mounted on said actuator for movement into and out of engagement with said driver and being biased toward operative engagement position therewith; a re-setting cam face on said interponent; a trigger normally holding said interponent disengaged from said driver; a key; and means responsive to depression of said key for actuating said trigger to release said interponent and enable it to move into engagement with said driver, and responsive to return movement of said key when said driver is at rest for moving said trigger reversely to move a part of said trigger against said re-setting cam face and thus move said interponent from engagement with said driver.

9. In a power operated typewriting or like machine, a frame, a carriage mounted for letter spacing and return travel on said frame; power driven mechanism including a member which rotates when the machine is in operation; normally disabled driving connections interposed between said member and said carriage and being adapted to be enabled for transmitting returning drive from said member to said carriage; a rotatable toothed driver operable concurrently with said rotatable member; an actuator for enabling said driving connections; an interponent pawl movably mounted on said actuator; a spring urging said pawl toward engagement with said driver; a trigger on said actuator normally maintaining said pawl disengaged from said driver; key controlled means for actuating said trigger in one direction to release said pawl and enable it to be moved into engagement with said driver, whereby said pawl and said actuator will be moved together until their travel as a unit moves said pawl out of engagement with said driver; and a device engageable by said trigger after disengagement of said pawl from said driver for moving said trigger in the reverse direction for re-setting said pawl in its normal position.

10. In a power operated typewriting or like machine, a frame, a carriage mounted for letter spacing and return travel on said frame; power driven mechanism including a member which rotates when the machine is in operation; normally disabled driving connections interposed between said member and said carriage and being adapted to be enabled for transmitting returning drive from said member to said carriage; a rotatable toothed driver operable concurrently with said rotatable member; an actuator for enabling said driving connections; an interponent pawl movably mounted on said actuator; a re-setting

cam on said pawl; a spring urging said pawl toward engagement with said driver; a trigger on said actuator normally maintaining said pawl disengaged from said driver; key controlled means for actuating said trigger in one direction to release said pawl and enable it to be moved into engagement with said driver, whereby said pawl and said actuator will be moved together until their travel as a unit moves said pawl out of engagement with said driver; and a device engageable by said trigger after disengagement of said pawl from said driver for moving said trigger in the reverse direction to cause a part of said trigger to press against said re-setting cam and thus return said pawl to its normal position.

11. In a power operated typewriting or like machine, a frame, a carriage mounted for letter spacing and return travel on said frame; power driven mechanism including a member which rotates when the machine is in operation; normally disabled driving connections interposed between said member and said carriage and being adapted to be enabled for transmitting returning drive from said member to said carriage; an actuator for enabling said driving connections; a driver rotatable concurrently with said rotatable member; an interponent mounted movably on said actuator; a spring urging said interponent to move into engagement with said driver; a trigger mounted movably on said actuator and normally occupying a position in which it maintains said interponent out of engagement with said driver; an abutment; and key controlled means or imparting to said actuator sufficient initial movement to move said trigger into engagement with said abutment to thereby move said trigger on said actuator and release said interponent to enable the latter to be moved by said spring into engagement with said driver.

12. In a power operated typewriting or like machine, a frame, a carriage mounted for letter spacing and return travel on said frame; power driven mechanism including a member which rotates when the machine is in operation; normally disabled driving connections interposed between said member and said carriage and being adapted to be enabled for transmitting returning drive from said member to said carriage; an actuator for enabling said driving connections; a driver operable concurrently with said rotatable member; and key controlled means for normally maintaining said actuator disconnected from said driver and being operable for effecting temporary driving connection of said actuator to said driver, said key controlled means including two spaced abutments and a control element having a part movable between said abutments, one side of said part being engageable with one of said abutments for effecting operative connection of said actuator to said driver and the other side of said part being engageable with the other of said abutments for restoring said element to its normal position.

13. In a power operated typewriting or like machine, a frame, a carriage mounted for letter spacing and return travel on said frame; power driven mechanism including a member which rotates when the machine is in operation; means including a normally disengaged clutch for transmitting returning drive from said member to said carriage; an actuator for engaging said clutch; a driver rotatable concurrently with said rotatable member; an interponent mounted movably on said actuator; a spring urging said interponent to move into engagement with said driver;

a trigger mounted movably on said actuator and normally occupying a position in which it maintains said interponent out of engagement with said driver; an abutment; and key controlled means for imparting to said actuator sufficient initial movement to move said trigger into engagement with said abutment to thereby move said trigger on said actuator and release said interponent to enable the latter to be moved by said spring into engagement with said driver.

14. In a power operated typewriting or like machine, a frame, a carriage mounted for letter spacing and return travel on said frame; power driven mechanism including a member which rotates when the machine is in operation; means including a normally disengaged clutch for transmitting returning drive from said member to said carriage; an actuator for engaging said clutch; a rotatable toothed driver operable concurrently with said rotatable member; an interponent pawl movably mounted on said actuator; a spring urging said pawl toward engagement with said driver; a trigger on said actuator normally maintaining said pawl disengaged from said driver; key controlled means for actuating said trigger in one direction to release said pawl and enable it to be moved into engagement with said driver, whereby said pawl and said actuator will be moved together until their travel as a unit moves said pawl out of engagement with said driver; and a device engageable by said trigger after disengagement of said pawl from said driver for moving said trigger in the reverse direction for re-setting said pawl in its normal position.

15. In a power operated typewriting or like machine, a frame; a carriage mounted for letter spacing and return travel on said frame; power driven mechanism including a member which rotates when the machine is in operation; means for transmitting returning drive from said member to said carriage including a normally disengaged clutch having an element mounted to shift for engaging the clutch; and means for shifting said element to clutch-engaging position including a first movably mounted part adapted to act on said element, a second movably mounted part; a resilient force transmitting connection between said two parts, a power operated driver; connections between said driver and said second part including an interponent biased to move into engagement with said driver to be driven thereby for effecting actuation of said second part to transmit force through said resilient connection to said first part to thereby apply cushioned shifting effort to said shiftable clutch element; a control element normally releasably maintaining said interponent disengaged from said driver; a key; means responsive to depression of said key for moving said control element to release said interponent and enable it to be moved by its bias into engagement with said driver; and means responsive to return movement of said key when said driver is not operating for returning said interponent to its normal position.

16. In a power operated typewriting or like machine, a frame; a carriage mounted for letter spacing and return travel on said frame; power driven mechanism including a member which rotates when the machine is in operation; means for transmitting returning drive from said member to said carriage including a normally disengaged clutch having an element mounted to shift for engaging the clutch; and means for

shifting said element to clutch-engaging position including a first lever adapted to act on said element, a second lever rockable independently of said first lever, a force transmitting spring connection between said levers; a power operated driver; connections between said driver and said second lever including an interponent biased to move into engagement with said driver to be driven thereby for rocking said second lever to transmit force through said spring to rock said first lever and apply cushioned shifting effort to said shiftable element; a control element normally releasably maintaining said interponent disengaged from said driver; a key; means responsive to depression of said key for moving said control element to release said interponent and enable it to be moved by its bias into engagement with said driver; and means responsive to return movement of said key when said driver is not operating for returning said interponent to its normal position.

17. In a power operated typewriting or like machine, a frame; a carriage mounted for letter spacing and return travel on said frame; power driven mechanism including a member which rotates when the machine is in operation; means for transmitting returning drive from said member to said carriage including a normally disengaged clutch having an element mounted to shift for engaging the clutch; and means for shifting said element to clutch-engaging position including a first movably mounted part adapted to act on said element, a second movably mounted part; a resilient force transmitting connection between said two parts, a power operated driver; connections between said driver and said second part including an interponent biased to move into engagement with said driver to be driven thereby for effecting actuation of said second part to transmit force through said resilient connection to said first part to thereby apply cushioned shifting effort to said shiftable clutch element; a control element normally releasably maintaining said interponent disengaged from said driver; a key; means responsive to depression of said key for moving said control element to release said interponent and enable it to be moved by its bias into engagement with said driver; a latch for releasably retaining said second movably mounted part in its actuated position; means operable in response to returning of the carriage to a predetermined position on said frame for releasing said latch; and means responsive to return movement of said key when said driver is not operating for returning said interponent to its normal position.

18. In a power operated typewriting or like machine, a frame; a carriage mounted for letter spacing and return travel on said frame; power driven mechanism including a member which rotates when the machine is in operation; means for transmitting returning drive from said member to said carriage including a normally disengaged clutch having an element mounted to shift for engaging the clutch; and means for shifting said element to clutch-engaging position including a first lever adapted to act on said element, a second lever rockable independently of said first lever, a force transmitting spring connection between said levers; a power operated driver; connections between said driver and said second lever including an interponent biased to move into engagement with said driver to be driven thereby for rocking said second lever to transmit force through said spring to

rock said first lever and apply cushioned shifting effort to said shiftable element; a control element normally releasably maintaining said interponent disengaged from said driver; a key; means responsive to depression of said key for moving said control element to release said interponent and enable it to be moved by its bias into engagement with said driver; a latch for releasably retaining said second lever in its rocked position; means operable in response to returning of the carriage to a predetermined position on said frame for releasing said latch; and means responsive to return movement of said key when said driver is not operating for returning said interponent to its normal position.

19. In a power operated typewriting or like machine, a frame; a carriage mounted for letter spacing and return travel on said frame; power driven mechanism including a member which rotates when the machine is in operation; means including a normally disengaged clutch for transmitting returning drive from said member to said carriage; a clutch engaging device; means for actuating said clutch engaging device including a driver, an actuator, an interponent mounted on said actuator and being biased to move into engagement with said driver, a control element normally releasably maintaining said interponent disengaged from said driver, a one-way-acting motion transmitting connection between said actuator and said clutch engaging device, and key controlled means for moving said control element to release said interponent and enable it to be moved by its bias into engagement with said driver whereby to cause said actuator to act momentarily through said one-way acting motion transmitting connection and actuate said device to engage said clutch; a latch for maintaining said device in actuated position after the momentary action of said actuator has terminated; and means responsive to return of said key controlled means to normal position when said driver is not operating for disengaging said interponent from said driver.

20. In a power operated typewriting or like machine, a frame; a carriage mounted for letter spacing and return travel on said frame; power driven mechanism including a member which rotates when the machine is in operation; means including a normally disengaged clutch for transmitting returning drive from said member to said carriage; a rockable clutch-engaging lever; an arm; a rockable shaft to which said arm is secured; a roller connection between said arm and said lever; a latch lever mounted to turn freely on said shaft; and means including a spring connected between said latch lever and said arm for urging said arm to rock for actuating said clutch engaging lever when said latch lever is rocked.

21. In a power operated typewriting or like machine, a frame; a carriage mounted for letter spacing and return travel on said frame; power driven mechanism including a member which rotates when the machine is in operation; means including a normally disengaged clutch for transmitting returning drive from said member to said carriage; a rockable clutch-engaging lever; an arm; a rockable shaft to which said arm is secured; a roller connection between said arm and said lever; a latch lever mounted to turn freely on said shaft; means including a spring connected between said latch lever and said arm for urging said arm to rock for actuating said clutch engaging lever when said latch lever is

rocked; and means including a one-way-acting motion transmitting connection for rocking said latch lever.

22. In a power operated typewriting or like machine, a frame; a carriage mounted for letter spacing and return travel on said frame; power driven mechanism including a member which rotates when the machine is in operation; means including a normally disengaged clutch for transmitting returning drive from said member to said carriage; a rockable clutch-engaging lever; an arm; a rockable shaft to which said arm is secured; a roller connection between said arm and said lever; a latch lever mounted to turn freely on said shaft; means including a spring connected between said latch lever and said arm for urging said arm to rock for actuating said clutch engaging lever when said latch lever is rocked; means including a momentarily operative actuator and a one-way-acting motion transmitting connection for rocking said latch lever; and a latch for releasably retaining said latch lever in rocked position.

23. In a power operated typewriting or like machine, a frame; a carriage mounted for letter spacing and return movements on the frame; power driven mechanism which rotates when the machine is in operation; driving connections between said mechanism and said carriage including a normally disengaged clutch; key con-
